(57) **CLAIM**

The ornamental design for an actuator for a portable electronic device, as shown and described.

DESCRIPTION

FIG. 1 is a first perspective view of an actuator for a portable electronic device with a portion of a portable electronic device showing our new design;

FIG. 2 is a second perspective view thereof;

FIGS. 3 and 4 are perspective views of the actuator in isolation; and,

FIG. 5 is a plan view of the actuator in isolation.

The broken line showing of a portion of a portable electronic device in FIGS. 1 and 2 is included for illustrative purposes only and forms no part of the claimed design.
